UNITED STATES PATENT OFFICE.

ALBERT N. LATTIN, OF HARTFORD, CONNECTICUT, ASSIGNOR TO S. STERNAU & CO., OF NEW YORK, N. Y., A COPARTNERSHIP.

DESIGN FOR A CRUMB-SCRAPER.

No. 39,839.

Specification for Design.

Patented Feb. 23, 1909.

Application filed December 11, 1908. Serial No. 467,108. Term of patent 7 years.

To all whom it may concern:

Be it known that I, ALBERT N. LATTIN, a citizen of the United States, residing in the city of Hartford, county of Hartford, and State of Connecticut, have invented a new, original, and ornamental Design for a Crumb-Scraper, of which the following is a specification, reference being had to the accompanying drawing, forming a part thereof.

In the drawing I have shown the design in plan in Figure 1, and in elevation in Fig. 2.

The design comprises a crumb scraper embodying a handle and a blade. The blade has a back which is raised and rolled over, forming a curved back, the rolled-over

portion extending to and including the end opposite the handle. The handle is formed by producing a narrowing of the structure, connected to the blade along curved lines. The free end of the handle is ornamented by an irregular depression, and between the depression and the blade is an elevation in the shape of a paragraph.

I claim:

The ornamental design of crumb scraper as shown and described.

ALBERT N. LATTIN.
